UNITED STATES PATENT OFFICE

2,386,383

CONTROLLING MECHANISM

Lee H. Cushman, Hamilton, Mass., assignor to
United Shoe Machinery Corporation, Flemington, N. J., a corporation of New Jersey

Application May 26, 1943, Serial No. 488,608

6 Claims. (Cl. 12—17)

This invention relates to means for producing a predetermined movement of a machine element, as a gage in a shoe machine.

In machines of the character of that made the subject of Letters Patent of the United States No. 1,118,484, Fowler, November 24, 1914, a shoe mounted upon a support is moved, under the guidance of gaging means, through a path which presents the periphery of an attached sole to tools acting upon it. At different parts of said periphery, it is desired that a tool shall act differently, as to vary the extension of the margin of the sole from the upper. An object of my invention is to produce such movement of a machine element by simple, compact and positively acting fluid-pressure mechanism. This object I attain by combining with an element which is to have a predetermined movement in engagement with the work during each operating cycle of the machine of which it is a part, a servo-motor having an element connected to move the machine element and including a valve provided by two members movable relatively to each other to control said servo-motor, and means acting under the power of the machine for imparting to the valve members their controlling cycle of relative movement for each operating cycle of the machine. The element moved is shown herein as the upper gage of a rounding and channeling machine, which is shifted with reference to a crease-gage to present the attached sole differently to the means for operating upon it. The motor with its valve mechanism is made the subject of a divisional application filed in the United States Patent Office on August 3, 1944, and bearing the Serial No. 547,943.

In the accompanying drawings,

Fig. 1 shows in side elevation my improved organization as part of a rounding and channeling machine for shoe-soles;

Fig. 2 is a central vertical longitudinal section through the controlling mechanism thereof;

Figs. 3 and 4 are transverse sections on the lines III—III and IV—IV, respectively, of Fig. 1 for a particular angular position of the valve-sleeve;

Figs. 5 and 6 are similar views on the lines V—V and VI—VI, respectively, of Fig. 1 for another position of the valve-sleeve;

Figs. 7 and 8 and Figs. 9 and 10 are transverse sections on the same planes as Figs. 3 and 4 and Figs. 5 and 6, respectively, for still other positions of the valve-sleeve;

Fig. 11 is a plan view of a shoe-sole with the angles indicated about its periphery, at which

changes in the projection of the edge from the upper may occur and also at 10° intermediate points; and

Figs. 12, 13, 14 and 15 are diagrams showing the relation between the angular movement of the effective work, the valve-ports and the valve-sleeve-openings, and corresponding, respectively, to the valve-positions appearing in Figs. 3 and 4, Figs. 5 and 6, Figs. 7 and 8, and Figs. 9 and 10.

In the machine of the previously mentioned patent, to a jack or shoe-support 10 is imparted a combined movement of rotation and translation, by mechanism a portion of which is shown at A. This advances the margin of a sole s attached to a jacked shoe S to receive the action of a constantly rotated rounding cutter or knife 12, and that of a channel-knife 14. With the channel-knife is associated a presser-foot 16, which is moved vertically to throw the knife into and out of action. The path of the sole-margin, as it advances past the operating tools, is more exactly determined by a crease-gage 18 and an upper-gage 20. The gage 18 is furnished by a horizontal plate, the reduced outer edge of which is adapted to enter the crease between the upper and the sole of the shoe, and is mounted for vertical adjustment on a sleeve 22, which may be fixed in different positions upon the machine-frame. It is shown as so engaging the cutter-hub, that the cutter 12 is adjusted with it. The body of the gage 20 may consist of a bar 24, pivoted at 26 to mechanism to be hereinafter described, it being guided by a slotted connection 28 to the crease-gage so it may share in the vertical adjustment of the latter. At the same time, its rearwardly curved upper-engaging portion 20 may be moved longitudinally into different relations to the crease-gage.

It may be desired that the sole-edge, as it is rounded by the cutter 12, shall project different distances from the upper. This variation in the sole-extension may be obtained by shifting the upper-gage outwardly or inwardly. In the present instance, it is assumed that the shank-portion of a sole-margin at opposite sides is to be narrower than that at the heel-seat and forepart. The controlling means of this invention effects the desired positioning of the work by fluid-pressure mechanism B, which comprises, as a unitary structure, a servo-motor by which the gage 20 is actuated and a valve by which it is controlled. Supported upon the frame of the machine is a casing 40, through the wall of which and spaced from each other longitudinally are inlet-ports 42 and 44, lying in the same vertical

plane longitudinally of the casing and supplied with fluid under pressure, preferably oil, through pipes 46 and 48, respectively. Alternating with the ports 42 and 44, and separated from these by 90° about the casing, are outlet-ports 50 and 52, to which are joined the respective pipes 54 and 56. Fitting within the casing is a valve-sleeve 58, the projecting hub 60 of which is joined by spiral gearing 62, a vertical shaft 64, bevel-gearing 66, a horizontal shaft 68 and bevel-gearing 70 to the cam-shaft 72 of the machine controlled. The ratio of the gearing is such that the valve-sleeve is rotated through 360° for each operating cycle of the machine, or while the cutter 12 is rounding the entire periphery of the soles of a jacked shoe. In the valve-sleeve are pairs of sets of openings which, in the rotation, successively register with corresponding casing-ports. The inlet-openings 74 and 76, which co-operate with the port 42, are elongated, each occupying about 180° of the circumference of the sleeve. The remaining openings may be of substantially the same area as the ports, the inlet-openings 78 and 80 corresponding to the port 44, and the outlet-openings 82 and 84 and 86 and 88 to the ports 50 and 52, respectively. Within the sleeve 58 a piston 90 is reciprocable, its rod 92 being guided in the sleeve-hub 60 and at the opposite end in the head of the casing 40. To a terminal-portion 94 of the rod the upper-gage 20, 24 is pivoted at 26. The movement of the gage toward the work is limited by a nut 96, threaded upon the outer end of the rod 92 and contacting with the outer face of the gear 62 upon the hub 60. In the opposite direction, the engagement of the terminal 94 with the casing-head determines the extent of travel. The piston 90, together with the valve-sleeve 58, furnishes a servo-motor which, governed by its valve 40, 58, will apply power to the upper-gage 20 to shift it in opposite directions, and thereby impart to the soles of a jacked shoe S the desired changes in contour.

For the purposes of this description, the form of the sole may be as previously indicated—a less projection of the edge from the upper at the opposite sides of the shank than at the heel-seat and forepart. Considering, as appears in Fig. 11, the zero point in the rotation of the sole-edge to be at the center of the rear of the sole, which is turning in the direction of the arrow, the narrower projection will be between 80° and 100° and between 260° and 280° of this rotation, with the wider margin from 100° to 260° at the forepart, and from 280° to 80° at the heel-seat. In each of Figs. 12, 13, 14 and 15 is shown diagrammatically the relation between the active ports in the casing 40 and the cooperating openings in the valve-sleeve 58, the positions to which the piston 90 is carried by the resulting pressure, and the angles in the rotation of the sole. The latter are designated by the line x, which may be considered as indicating the point of operation of the cutter 12. Each figure is based upon a development of the valve-sleeve, which is divided transversely by lines each indicating 10° of rotation of the sole and valve-sleeve. Assume the jack 10 to have rotated through 280°, and that there is to occur the change from the narrower shank to the wider heel-seat margin. At this time, as appears in Fig. 12, the sleeve-opening 74 will have arrived at the inlet-port 42 (Fig. 3), while the sleeve-opening 82 (Fig. 4) will register with the outlet-port 50 (Fig. 4). Oil under pressure will be supplied to the right-hand end of the sleeve 58 (Figs. 1 and 2), which furnishes

a cylinder for the piston 90 of the servo-motor, as well as a portion of the valve. This forces the piston forward from the position illustrated in Fig. 15 until it is arrested by the contact of the nut 96 with the gear 62. The work, which has been positioned by the crease-gage 18, is at once carried outward by the pressure of the gage 20 against the upper, and the edge of the sole is shifted in the field of action of the cutter 12, so that a wider rounded margin is left upon the sole. During the succeeding 160° of rotation of the work and 90° of rotation of the valve-sleeve, although the outlet-port 50 has been closed by the passing of the valve-sleeve-opening 82, the elongated sleeve-opening 74 will hold the upper-gage firmly out in the desired relation. At 80° in the rotation of the jack beyond the zero-point (Fig. 13), the sleeve-openings 78 and 86 respectively reach the inlet-port 44 (Fig. 5) and the outlet-port 52 (Fig. 6), the port 42 having been closed by the passing of the sleeve-opening 74. Pressure is applied to the opposite side of the piston 90 to retract the upper-gage until the rod-terminal 94 strikes the casing-head. This so withdraws the gage 20 that the jack mechanism carries the shoe in until the crease is seated upon the gage 18, the upper-gage 20 becoming ineffective. A narrow edge results, and no continued fluid-pressure need be exerted at this time to hold the upper-gage in place, the work itself effecting this. 20° more of rotation of the sole having occurred, the elements are as appears in Fig. 14. The arrival of the sleeve-opening 76 at the inlet-port 42 (Fig. 7) and the sleeve-opening 84 at the outlet-port 50 (Fig. 8) creates conditions similar to those of the first period. The resulting pressure upon the piston 90 again urges the gage 20 out to remove the work from the gage 18, and thus widen the sole-edge about the forepart between 100° and 260° of work-rotation. Finally, as may be seen in Fig. 15, the narrowing edge at the shank between 260° and 280° of work-rotation is produced by the withdrawal of the upper-gage by pressure applied to the piston 90 through the inlet-port 44 and sleeve-opening 80 (Fig. 9), and exhaust is permitted through the sleeve-opening 88 and the outlet-port 52 (Fig. 10). An operating cycle of the machine has thus been completed. It will be seen that throughout this cycle, the work and the valve-sleeve rotate in synchronism, and that, by a correct location of the ports and co-operating openings for any period of angular movement of the valve-sleeve, a machine-operation may be produced at the time and of the duration desired.

Having described my invention, what I claim as new and desire to secure by Letters Patent of the United States is:

1. In combination, a machine provided with an element for operating upon the work and having a predetermined movement in engagement with said work during each operating cycle of the machine, a servo-motor having an element connected to move the machine element and also including a valve provided by two members movable relatively to each other to control the servo-motor, and means acting under the power of the machine for imparting to the valve members a controlling cycle of relative movement for each operating cycle of the machine.
2. In combination, a machine provided with an element for operating upon the work and having a predetermined movement in engagement with said work during each operating cycle of the machine, a rotatable valve-cylinder provided

with openings, means for supplying fluid-pressure to and exhausting it from the cylinder through the valve-openings, a piston movable in the cylinder and connected to move the machine element, and means for rotating the valve-cylinder to a predetermined extent during each operating cycle of the machine.

3. In a shoe machine, means for operating upon a shoe, a gage by which the shoe is positioned for the operation upon it, and fluid-pressure mechanism for moving the gage to present the shoe differently to the operating means, said mechanism including a valve movable under the power of the machine through a gage-controlling cycle for each operating cycle of the machine. 10

4. In a shoe machine, means for operating upon a shoe, a gage by which the shoe is positioned for the operation upon it, a casing, a valve-sleeve rotatable in the casing, the casing being provided with inlet- and outlet-ports and the sleeve with openings movable into registration with the ports, and a piston movable in the sleeve and connected to the gage. 20

5. In a sole-rounding machine, a rounding cut-

ter, a shoe-support, means for moving the support to present the periphery of the sole of a supported shoe to the cutter, a crease-gage for guiding the shoe during a portion of the operation, an upper-gage by which the shoe is guided during another portion of the operation, and fluid-pressure mechanism arranged to move the upper-gage both into and out of active position during each operating cycle of the machine.

6. In a sole-rounding and channeling machine, rounding and channeling cutters, a shoe-support, means for moving the support to present the periphery of a sole to the cutters, a crease-gage for guiding the shoe during a portion of the operation, an upper-gage by which the shoe is guided during another portion of the operation, fluid-pressure mechanism by which the upper-gage is moved into and out of active position, said mechanism including a rotatable valve member, and means for rotating the valve member under the power of the machine once during each operating cycle of the machine. 20

LEE H. CUSHMAN.
